ADDUCTS OF HETERO CYCLIC AMIDES

Newman M. Bortnick, Oreland, Pa., assignor to Rohm & Haas Company, Philadelphia, Pa., a corporation of Delaware

No Drawing. Application December 5, 1956
Serial No. 626,311

24 Claims. (Cl. 260—244)

This invention concerns adducts of heterocyclic amides and specific α,β -unsaturated compounds. It further deals with a method of preparation for these adducts.

The heterocyclic amides employed in this invention may be represented by the formula

in which L is a three- to four-membered divalent chain containing two to three carbon atoms and one oxygen atom, and Y is a chalcogen having an atomic weight of sixteen to thirty-two, i. e., oxygen or sulfur. The carbon atoms in the L chain may have their remaining valences satisfied by hydrogen atoms, by alkyl groups whose total carbon atom content is no greater than eighteen, or by combination of hydrogen and alkyl groups. When L contains two carbon atoms there are four valences to be satisfied by hydrogen atoms, alkyl groups, or combinations thereof. For instance, there may be four hydrogen atoms, four alkyl groups, three hydrogen atoms and one alkyl group, two hydrogen atoms and two alkyl groups, or one hydrogen atom and three alkyl groups. When L contains three carbon atoms there are six valences to be satisfied by hydrogen atoms, alkyl groups, or combinations thereof and these valences may be satisfied in a way analogous to the manner described above when L contained two carbon atoms. It is also possible for the above-mentioned alkyl substituents to be joined together to form carbocyclic rings in conjunction with the L chain.

It is preferred that the oxygen atom in the L chain be vicinal to the carbonyl group in the heterocyclic amide. The alkyl substituents on the carbon atoms of the L chain may have any possible spatial configuration such as normal, iso-, tertiary, and the like. Typically, these alkyl substituents may also be straight chained or cyclic. Typical of the alkyl substituents that may be used to satisfy the remaining valences of the carbon atoms in the L chain include methyl, ethyl, propyl, butyl, cyclopentyl, hexyl, cyclohexyl, octyl, decyl, dodecyl, tridecyl, tetradecyl, and octadecyl groups.

Illustrative of the heterocyclic amides that may be employed as reactants in the present invention include 2-oxazolidinone, 4-oxazolidinone, 3-isooxazolidinone, tetrahydro-1,3-oxazin-2-one, 1,4-oxazin-3-one, 1,3-oxazin-4-one, 1,2-oxazin-3-one, 5-methyl-2-oxazolidinone, 4,5-dimethyl-2-oxazolidinone, 5-butyl-2-oxazolidinone, 4-propyl-5-octyl-2-oxazolidinone, 4-cyclohexyl-2-oxazolidinone, 4-ethyl-5-dodecyl-2-oxazolidinone, 4,4,5,5-tetramethyl-2-oxazolidinone, 4-octadecyl-2-oxazolidinone, 2-methyl-4-oxazolidinone, 2,5-dipropyl-4-oxazolidinone, 2,2,5,5-tetramethyl-4-oxazolidinone, 2-cyclopentyl-4-oxazolidinone, 2-cyclotetradecyl-4-oxazolidinone, 4,5-dipropyl-3-isooxazolidinone, 4-decyl-3-isooxazolidinone, 4-ethyl-5-hexadecyl-3-isooxazolidinone, 4,5,6-trimethyltetrahydro-1,3-oxazin-2-thione, 4,5,6-triethyltetrahydro-1,3-oxazin-2-thione, 5-dodecyltetrahydro-1,3-oxazin-2-thione, 4-hexyl-6-octyltetrahydro-1,3-oxazin-2-thione, 5-decyltetrahydro-1,3-oxazin-2-thione, 2,5,6,6-tetraethyltetrahydro-1,2-oxazin-3-one, 4-ethyltetrahydro-1,2-oxazin-3-one, 4,4,5,6-tetraethyltetrahydro-1,2-oxazin-3-one, 4,5,6-tripropyltetrahydro-1,2-oxazin-3-one, 5,5-dibutyltetrahydro-1,2-oxazin-3-one, 4-butyl-6-octyltetrahydro-1,2-oxazin-3-one, 4-decyl-6-propyltetrahydro-1,2-oxazin-3-one, 4-dodecyl-5-ethyl-6-butyltetrahydro-1,2-oxazin-3-one, 5-hexadecyltetrahydro-1,2-oxazin-3-one, 5-decyltetrahydro-1,2-oxazin-3-one, 2-oxazolidinethione, 4-oxazolidinethione, 3-isooxazolidinethione, tetrahydro-1,3-oxazin-2-thione, tetrahydro-1,4-oxazin-3-thione, tetrahydro-1,3-oxazin-4-thione, tetrahydro-1,2-oxazin-3-thione, 4-dimethyl-2-oxazolidinethione, 4-butyl-5-hexyl-2-oxazolidinethione, 4-dodecyl-2-oxazolidinethione, 2,2,5,5-tetramethyl-4-oxazolidinethione, 2,2-diethyl-4-oxazolidinethione, 2-propyl-5-pentyl-4-oxazolidinethione, 2-cyclopentyl-4-oxazolidinethione, 2-tetradecyl-4-oxazolidinethione, 4,5-dipropyl-3-isooxazolidinone, 4-decyl-3-isooxazolidinethione, 4-ethyl-5-hexadecyl-3-isooxazolidinethione, 4,5,6-trimethyltetrahydro-1,3-oxazin-2-thione, 4,5,6-triethyltetrahydro-1,3-oxazin-2-thione, 5-dodecyltetrahydro-1,3-oxazin-2-thione, 4-hexyl-6-octyltetrahydro-1,3-oxazin-2-thione, 5-decyltetrahydro-1,3-oxazin-2-thione, 2,5,6,6-tetraethyltetrahydro-1,4-oxazin-3-thione, 2-ethyl-5-propyl-6-butyltetrahydro-1,4-oxazin-3-thione, 2-pentyl-6-decyltetrahydro-1,4-oxazin-3-thione, 5-butyl-6-tetradecyltetrahydro-1,4-oxazin-3-thione, 2,2,5,6-tetramethyltetrahydro-1,3-oxazin-4-thione, 2-butyl-6-cyclohexyltetrahydro-1,3-oxazin-4-thione, 5-decyl-6-hexyltetrahydro-1,3-oxazin-4-thione, 4,4,6,6-tetramethyltetrahydro-1,2-oxazin-3-thione, 5,5-dibutyltetrahydro-1,2-oxazin-3-thione, 4,5,6-tripentyltetrahydro-1,2-oxazin-3-thione, and 4-propyl-6-pentadecyltetrahydro-1,2-oxazin-3-thione.

The α,β -unsaturated compounds employed in this invention correspond to the formula

in which Q is a hydrogen atom, an alkyl group of one to eight carbon atoms, or the group

to be more fully described hereinafter. T may stand for a cyano group, the group $-\text{CONZ}_2$ in which Z may stand for a hydrogen atom or an alkyl group of one to four carbon atoms, or the group $-\text{COOR}$. The symbol R represents a monovalent esterifying group of preferably

one to fourteen carbon atoms and, preferably, alkyl groups of one to fourteen carbon atoms, alkoxyalkyl groups of two to fourteen carbon atoms, aralkyl and alkarylalkyl groups of seven to fourteen carbon atoms, and cycloalkyl and alkylcycloalkyl groups of three to fourteen carbon atoms. The alkyl groups may be straight or branched chains in any of the known spatial configurations. The alkyl groups positioned on cyclic structures may occupy any possible ring location.

Typical of the representations of Q include a hydrogen atom, the groups methyl, ethyl, propyl, butyl, hexyl, and octyl, and the groups $-\text{CH}_2\text{CH}_2\text{CH}(\text{CH}_3)-\text{T}$.

Typical of the groups that may be employed as T include cyano, carbamoyl, methylcarbamoyl, ethylcarbamoyl, propylcarbamoyl, butylcarbamoyl, dimethylcarbamoyl, diethylcarbamoyl, dibutylcarbamoyl, methyl-ethylcarbamoyl, ethylbutylcarbamoyl, propylbutylcarbamoyl, methoxycarbonyl, ethoxycarbonyl, propoxycarbonyl, butoxycarbonyl, octoxycarbonyl, dodecoxy carbonyl, tetradecoxycarbonyl, methoxymethoxycarbonyl, methoxyethoxycarbonyl, methoxypropoxycarbonyl, methoxybutoxycarbonyl, methoxyoctoxycarbonyl, methoxydecoxycarbonyl, ethoxymethoxycarbonyl, ethoxyethoxycarbonyl, ethoxypropoxycarbonyl, ethoxyoctoxycarbonyl, propoxymethoxycarbonyl, propoxypentoxycarbonyl, propoxymethoxycarbonyl, butoxymethoxycarbonyl, butoxymethoxycarbonyl, butoxybutoxycarbonyl, butoxynonoxy carbonyl, butoxydecoxycarbonyl, pentoxymethoxycarbonyl, pentoxybutoxycarbonyl, pentoxyoctoxycarbonyl, hexoxymethoxycarbonyl, hexoxypropoxycarbonyl, hexoxyhexoxycarbonyl, hexoxyoctoxycarbonyl, heptoxymethoxycarbonyl, heptoxybutoxycarbonyl, heptoxyheptoxy carbonyl, octoxymethoxycarbonyl, octoxyethoxycarbonyl, octoxybutoxycarbonyl, octoxyhexoxycarbonyl, benzoxycarbonyl, phenylethoxycarbonyl, phenylbutoxycarbonyl, ethylbenzoxycarbonyl, phenylbutoxycarbonyl, phenylhexoxycarbonyl, phenyloctoxycarbonyl, butylbenzoxycarbonyl, naphthylmethoxycarbonyl, naphthylethoxycarbonyl, naphthylpropoxycarbonyl, naphthylbutoxycarbonyl, cyclopropoxycarbonyl, cyclobutoxycarbonyl, cyclo pentoxycarbonyl, cyclohexoxycarbonyl, butylcyclopentoxycarbonyl, octylcyclohexoxycarbonyl, cyclopentylheptoxycarbonyl, and cyclohexylcoxycarbonyl.

Illustrative of the α,β -unsaturated compounds that may be used as reactants in this invention include acrylonitrile, methacrylonitrile, α -butylacrylonitrile, α -octylacrylonitrile, acrylamide, methacrylamide, α -ethylacrylamide, α -propylacrylamide, α -octylacrylamide, N-methylacrylamide, N,N-dimethylacrylamide, N-ethylmethacrylamide, N-ethyl-N-propylmethacrylamide, N-methyl- α -ethylacrylamide, N-methyl-N-butyl- α -propylacrylamide, N,N-di-(2-ethylhexyl)acrylamide, N,N-dimethyl- α -octylacrylamide, methyl acrylate, ethyl acrylate, butyl acrylate, octyl acrylate, dodecyl acrylate, tetradecyl acrylate, methyl methacrylate, butyl methacrylate, decyl methacrylate, methyl ethacrylate, ethyl ethacrylate, octyl ethacrylate, methyl α -propylacrylate, butyl α -propylacrylate, nonyl α -propylacrylate, methyl α -butylacrylate, propyl α -butylacrylate, heptyl α -butylacrylate, methyl α -hexylacrylate, butyl α -heptylacrylate, undecyl α -hexylacrylate, butyl α -octylacrylate, methyl α -octylacrylate, dodecyl α -octylacrylate, methoxyethyl acrylate, methoxydecyl acrylate, ethoxypropyl acrylate, butoxyhexyl acrylate, methoxymethyl methacrylate, propoxydecyl methacrylate, ethoxyethyl ethacrylate, butoxyoctyl ethacrylate, methoxydodecyl α -propylacrylate, pentoxypentyl α -propylacrylate, methoxybutyl α -butylacrylate, butoxyhexyl α -butylacrylate, ethoxyheptyl α -pentylacrylate, methoxyoctyl α -hexylacrylate, propoxybutyl α -heptylacrylate, butoxybutyl α -octylacrylate, benzyl acrylate, naphthylmethyl acrylate, phenylethyl methacrylate, naphthylethyl methacrylate, benzyl ethacrylate, naphthylbutyl

ethacrylate, phenyloctyl α -propylacrylate, naphthylethyl α -butylacrylate, octylphenylethyl α -pentylacrylate, benzyl α -hexylacrylate, naphthylmethyl α -heptylacrylate, phenylhexyl α -octylacrylate, cyclohexyl acrylate, cyclopentyl methacrylate, cyclohexyl ethacrylate, cyclobutyl α -octylacrylate, dimethyl α -methylene- α' -methyladipate, methyl hexyl α -methylene- α' -methyladipate, dimethoxyethyl α -methylene- α' -methyladipate, hexoxyethyl methyl α -methylene- α' -methyladipate, methyl benzyl α -methylene- α' -methyladipate, dibenzyl α -methylene- α' -methyladipate, methyl cyclohexyl α -methylene- α' -methyladipate, dicyclopentyl α -methylene- α' -methyladipate, methyl octylcyclohexyl α -methylene- α' -methyladipate, ethyl naphthylethyl α -methylene- α' -methyladipate, α -methylene- α' -methyladiponitrile, α -methylene- α' -methyladipamide, N,N'-dimethyl- α -methylene- α -methyladipamide, N,N'-dibutyl- α -methylene- α' -methyladipamide, N-butyl- N -methyl- α -methyleneadipamide, N,N,N'-tetramethyl- α -methylene- α' -methyladipamide, 2-methylene-5-cyanohexanamide, N-methyl-2-methylene-5-cyanohexanamide, N,N-diethyl-2-methylene-5-cyanohexanamide, 2-methyl-5-cyano-5-hexenamide, N-methyl-2-methyl-5-cyano-5-hexenamide, N,N-dimethyl-2-methyl-5-cyano-5-hexenamide, N-methyl-N-butyl-2-methylene-5-cyanohexanamide, 2-methyl-5-cyano-5-hexenoate, butoxyethyl 2-methyl-5-cyano-5-hexenoate, pentoxypentyl 2-methyl-5-cyano-5-hexenoate, benzyl 2-methyl-5-cyano-5-hexenoate, naphthylethyl 2-methyl-5-cyano-5-hexenoate, cyclohexyl 2-methyl-5-cyano-5-hexenoate, methyl 2-methylene-5-cyanohexanoate, octyl 2-methylene-5-cyanohexanoate, methoxyethyl 2-methylene-5-cyanohexanoate, butoxybutyl 2-methylene-5-cyanohexanoate, octylphenylethyl 2-methylene-5-cyanohexanoate, naphthylbutyl 2-methylene-5-cyanohexanoate, cyclopentyl 2-methylene-5-cyanohexanoate, methyl 2-methylene-5-cyano-5-hexenoate, ethyl 2-methyl-5-carbamoyl-5-hexenoate, decyl 2-methyl-5-dimethylcarbamoyl-5-hexenoate, ethoxyethyl 2-methyl-5-methylpropylcarbamoyl-5-hexenoate, octoxybutyl 2-methyl-5-butylcarbamoyl-5-hexenoate, benzyl 2-methyl-5-ethylcarbamoyl-5-hexenoate, cyclohexyl 2-methyl-5-carbamoyl-5-hexenoate, butyl 2-methylene-5-carbamoylhexanoate, tetradearyl 2-methylene-5-carbamoylhexanoate, methoxyhexyl 2-methylene-5-methylcarbamoylhexanoate, butoxypropyl 2-methylene-5-diethylcarbamoylhexanoate, benzyl 2-methylene-5-methylcarbamoylhexanoate, naphthylpropyl 2-methylene-5-propylcarbamoylhexanoate, and cyclopentyl 2-methylene-5-dipropylcarbamoylhexanoate.

The reactants of this invention are compounds that are known or can be made by known methods. The reactants unite on a substantially mole for mole basis.

The products of this invention are made by bringing together at a reacting temperature in the presence of a strong alkaline catalyst a compound having the formula

with one having the formula

in which the symbols have the significance previously set forth. Temperatures in the range of about 0° to 200° C. are advantageously employed, with a range of about 25° to 175° C. preferred.

The α,β -unsaturated compounds are all liquids and the heterocyclic amides are generally solids. Since at least one of the reactants is always a liquid a solvent is not absolutely necessary. However, in many instances, it is advantageous to employ an inert volatile organic

solvent such as methanol, ethanol, butanol, benzene, toluene, xylene, dioxane, diethyl ether, dimethyl ether of ethylene glycol, and the like. At the conclusion of the reaction the solvent is readily removed such as by stripping, preferably at reduced pressures.

The present reaction is exothermic in nature and it is frequently advantageous to conduct the reaction by first adding all of the predetermined equivalent amount of the selected heterocyclic amide reactant to a reaction vessel along with the catalyst and a portion of the predetermined equivalent amount of the α,β -unsaturated compound reactant. In some cases, the above mixture requires some heating in order to initiate the reaction, after which a considerable heat of reaction becomes apparent. As the heat of reaction abates, additional portions of the α,β -unsaturated compound are introduced into the reaction vessel until all of the predetermined amount has been used. By using the above-described procedure, the present reaction is consistently conducted in an orderly manner. In many instances, it is entirely satisfactory to introduce all of the predetermined amounts of both of the reactants, particularly when the reactants have the higher molecular weights or substituent groups occupying considerable molecular space or both, in which situations a retarding ponderal effect is readily observable.

The time of reaction is not critical. Generally, times of about one-half hour to twenty-four hours are used, as conditions indicate. It is usually advantageous to conduct the present method for about an hour or two after the heat of reaction is finally dissipated. This is to maximize yields. Otherwise, the reaction may be concluded as one skilled in the art finds desirable.

A strong alkaline catalyst is used to effect the present method. Typical in this respect are alkali metals such as lithium, sodium, and potassium; alkali metal oxides such as lithium oxide, sodium oxide, and potassium oxide; alkali metal lower alkoxides such as lithium butoxide, sodium methoxide, and potassium ethoxide; alkali metal hydrides such as sodium hydride and potassium hydride; alkali metal amides such as sodium amide, lithium amide, and potassium amide; alkali metal lower alkyls and alkenyls such as methyl lithium, ethyl sodium, butyl potassium, allyl sodium, and butenyl potassium; phenylalkyl alkali metals such as benzyl sodium, phenylisopropyl potassium, and alkali metal aromatics such as phenyl sodium, phenyl lithium and phenyl potassium, phenyl butyl sodium; "Alfin" catalysts, which are commercial mixtures of alkali metal alkenyls and alkali metal alkenoxides, such as allyl sodium with sodium allyloxide and butenyl potassium with sodium butenyl-oxide; and quaternary ammonium bases such as trimethylbenzylammonium hydroxide and dimethyldibenzylammonium hydroxide and the corresponding alkoxides such as trimethylbenzylammonium butoxide, choline methoxide, and the like.

Yields up to 90% and over are consistently obtained. In some instances if appreciable amounts of impurities are present in the reactants the yields are somewhat reduced. Accordingly, it is preferred to employ reactants of as high a degree of purity as is conveniently and economically feasible.

At the conclusion of the reaction there may be added to the reaction system enough anhydrous mineral acid such as sulfuric, phosphoric, or the like, to neutralize the catalyst. The salt formed may be removed such as by filtration. Otherwise, the reaction system may be washed with water and the aqueous layer separated or decanted when the product is a solid. Any solvent employed may be stripped off, preferably under reduced pressure. Unused reactants when present may be washed out with water or stripped off under reduced pressure. If the product is a liquid it may be distilled, if desired. Solid products may be recrystallized in a conventional manner from

a suitable solvent such as hexane, heptane, benzene, toluene, ethylene dichloride, chloroform, or the like.

While the products of this invention may be quite satisfactorily prepared according to the foregoing discussion, 5 it may be advantageous in some instances, where ester groups are concerned and the desired R group is not lower alkyl, to first prepare the lower alkyl ester product and then make the desired higher molecular weight ester product by transesterification. This modification may be 10 used, if desired, to transesterify a single ester group or two ester groups, depending of course on the particular product contemplated.

Transesterification may be conducted preferably in the presence of a strongly acidic esterifying catalyst including 15 sulfuric acid, a lower alkanesulfonic acid, such as butanesulfonic acid, and an arylsulfonic acid, such as p-toluenesulfonic acid. It is, also, possible to employ a strongly acidic ion-exchange resin, such as a sulfonated polystyrene or sulfonated phenolformaldehyde resin.

20 Transesterification is preferably conducted at the reflux temperature of the reaction mixture, which is usually in the range of about 100° to 275° C., preferably in the range of about 150° to 225° C. The pressure is adjusted, when necessary, to conform to the above temperatures. 25 Also, if desired, small amounts of an inert volatile organic solvent, such as toluene, xylene, or the like, may be used to help regulate the reflux temperature. A lower alkanol is distilled off as the transesterification progresses and the reaction is continued until the theoretical amount 30 is collected.

At the termination of the transesterification, the product is isolated such as by neutralizing the catalyst, filtering, and distilling, preferably under reduced pressure.

The products of this invention have a wide variety of 35 valuable utilities. The lower molecular weight members are excellent solvents for polymers particularly those in which acrylonitrile or a vinyl ester is the major component. The liquid members are useful as synthetic lubricants in which instances they consistently exhibit 40 high viscosity indexes, low pour points, and low volatilities. The present products are useful as plasticizers, particularly for polyvinyl chloride. For instance, a mixture of 28 parts of 3-(2-methoxycarbonylethyl)-2-oxazolidinone, 44 parts of polyvinyl chloride, 0.75 part of tribasic lead sulfate, and 0.4 part of stearic acid milled for seven minutes at 325° F. gave a tough, flexible film of 45 good quality. Comparable results are obtained with the other products of this invention. The present products are effective fungicides when applied against *Stemphylium sarcinaeforme* and especially *Monilinia fructicola* in concentrations up to 1.0% in an inert carrier. These products are at the same time non-phytotoxic in 50 concentrations approaching 1% as determined on tomato plants in a standard test.

55 The method and compounds of this invention may be more fully understood from the following examples which are offered by way of illustration but not by way of limitation. Parts by weight are used throughout.

60

Example 1

65 There are added to a reaction vessel equipped with a stirrer, a thermometer, and a condenser 17.4 parts of 2-oxazolidinone and .25 part of sodium methoxide. There is then added at a rapid rate 17.2 parts of methyl acrylate. After the initial exothermic heat of reaction 70 subsides another 0.25 part portion of sodium methoxide is added. The reaction mixture is heated to reflux (102° C.) and maintained at this temperature for two hours. The reaction mixture is then distilled and the product collected as distillate. The product distills at 147° to 155° C. at 0.05 mm. absolute pressure. The 75 product has an n_D^{20} value of 1.4665 and is identified as

3-(2-methoxycarbonylethyl)-2-oxazolidinone. The product has the formula

In a similar manner there are prepared 3-(2-cyanoethyl)-5-methyl-2-oxazolidinone from 5-methyl-2-oxazolidinone and acrylonitrile, 2-octyl-3-(2-carbamoylethyl)-4-oxazolidinone from 2-octyl-4-oxazolidinone and acrylamide and 2-[2,5-bis(methoxycarbonyl)hexyl]-4,4-dibutyl-3-isooxazolidinone from 4,4-dibutyl-3-isooxazolidinone and dimethyl α -methylene- α' -methyladipate.

Example 2

There are added to a reaction vessel 20.2 parts of tetrahydro-1,3-oxazin-2-one and one part of sodium methoxide. There is added over a period of five minutes 25 parts of ethyl acrylate. The reaction mixture is heated to 95° C. and over a period of three hours there are added in four additions one part of sodium methoxide. The temperature is slowly increased to 135° to 140° C. and held at that level for one hour. The catalyst is neutralized with phosphoric acid and the product isolated by distillation. The product is identified as 3-(2-ethoxycarbonylethyl)tetrahydro-1,3-oxazin-2-one.

In an analogous way using sodium amide as a catalyst there are made 3-(2-dodecoxycarbonylethyl)-4,6-dimethyltetrahydro-1,3-oxazin-2-one from 4,6-dimethyltetrahydro-1,3-oxazin-2-one and dodecyl acrylate, 4-(2-carbamoylethyl)-2,6-diethyltetrahydro-1,4-oxazin-3-one from 2,6-diethyltetrahydro-1,4-oxazin-3-one and acrylamide, and 2-butyl-3-(2-cyanopropyl)-6-octyltetrahydro-1,3-oxazin-4-one from 2-butyl-6-octyltetrahydro-1,3-oxazin-4-one and methacrylonitrile.

Example 3

Into a reaction vessel there are added 14.3 parts of 4,4,5,5-tetramethyl-2-oxazolidinone and 0.25 part of sodium methoxide. Over a 10-minute period there is added 19.2 parts of butyl acrylate. The temperature of the reaction system rises from the exothermic heat of reaction. There is then introduced 0.50 additional part of sodium methoxide in two equal installments 20 minutes apart. The temperature of the reaction mixture is maintained at 105° to 115° C. for three hours. The catalyst is neutralized by the addition of phosphoric acid and the product is isolated by distillation. The product is identified as 3-(2-butoxycarbonylethyl)-4,4,5,5-tetramethyl-2-oxazolidinone.

In like manner, employing lithium oxide as catalyst there are prepared 3-(2-carbamoylpropyl)-5-decyl-2-oxazolidinethione from 5-decyl-4-oxazolidinethione and methacrylamide, 2,5-dimethyl-3-(2,5-dibenzylloxycarbonylhexyl)-tetrahydro-1,3-oxazin-4-thione from 2,5-dimethyltetrahydro-1,3-oxazin-4-thione and dibenzyl- α -methylene- α' -methyladipate, and 2-(2-cyanoethyl)-4,5-diethyltetrahydro-1,2-oxazin-3-thione from 4,5-diethyltetrahydro-1,2-oxazin-3-thione and acrylonitrile.

Example 4

There are introduced into a reaction vessel five parts of 3-isooxazolidinone and 0.25 part of potassium ethoxide. The mixture is heated to 72° C. and ten parts of methyl methacrylate is added over a period of ten minutes causing the temperature to rise. After 30 minutes there is then added 0.25 part of potassium ethoxide causing a further temperature rise. When the heat of reaction abates the mixture is heated at 130° to 136° C. for 40 minutes. The catalyst is neutralized by the addition of phosphoric acid and the product is isolated by distillation. The product corresponds to 2-(2-methoxycarbonylpropyl)-3-isooxazolidinone.

In an analogous way using dimethyl dibenzyl am-

monium butoxide as catalyst there are made 2-octadecyl-3-(2-dimethylcarbamoylethyl)-2-oxazolidinone from 2-octadecyl-2-oxazolidinone and N,N-dimethylacrylamide, 2-(2-octoxycarbonylpropyl)-5,5-dibutyl-3-isooxazolidinethione from 5,5-dibutyl-3-isooxazolidinethione and octoxymethacrylate, and 3-(2,5-dibutoxybutoxycarbonylhexyl)-5-hexyl-2-oxazolidinone from 5-hexyl-2-oxazolidinone and dibutoxybutyl- α -methylene- α' -methyladipate.

10

Example 5

There are introduced into a reaction vessel 20.2 parts of tetrahydro-1,3-oxazin-2-one and two parts of potassium butoxide. There is added 20 parts of diethyl- α -methylene- α' -methyladipate over a period of 15 minutes.

15

The reaction mixture is heated to 82° C. and 1.2 parts of potassium butoxide is added. There is then added dropwise 25 parts of diethyl α -methylene- α' -methyladipate and one part of potassium butoxide. The reaction mixture is heated at 98° to 120° C. for two and one-half hours. There are then added 300 parts of toluene and 100 parts of an aqueous 20% solution of sodium carbonate. The reaction mixture is stirred rapidly and the organic layer is separated, washed with 100 parts of aqueous 10% phosphoric acid, and then washed with 100 parts of water. The organic layer is stripped to 160° C. at 0.1 mm. absolute pressure leaving the product as the residue. The product is identified as 3-(2,5-diethoxycarbonylhexyl)-tetrahydro-1,3-oxazin-2-one.

20

In a similar way using the sodium methoxide catalyst there are made 2-(2,5-dicarbamoylhexyl)-tetrahydro-1,2-oxazin-3-one from tetrahydro-1,2-oxazin-3-one and 2-methylene-5-methyladipamide, 3-(2,5-dicyanohexyl)-4-butyl-5-octyl-2-oxazolidinethione from 4-butyl-5-octyl-2-oxazolidinethione and 2-methylene-5-methyladiponitrile, and 3-(2-carbamoyl-5-cyanohexyl)-6-dimethyltetrahydro-1,3-oxazin-4-one from 6,6-dimethyltetrahydro-1,3-oxazin-4-one and 2-methylene-5-cyanohexanamide.

25

Example 6

Into a reaction vessel there are added 47 parts of tetrahydro-1,3-oxazin-2-thione, 200 parts of toluene and three parts of potassium hydride. There is then added dropwise over a period of 90 minutes 30 parts of acrylonitrile at such a rate that the temperature of the reaction mixture, maintained by the exothermic heat of reaction, is kept below 100° C. The reaction mixture is then allowed to stand for one hour. The toluene layer is removed and anhydrous phosphoric acid is added to neutralize the catalyst. The toluene is removed by stripping at reduced pressure and the product is added by distillation at reduced pressure. The product corresponds to 3-(2-cyanoethyl)-tetrahydro-1,3-oxazin-2-thione.

30

In like manner, there are made 2-(5-dimethylcarbamoyl-2-cyanoethyl)-4,5,5-trimethyltetrahydro-1,2-oxazin-3-thione from 4,5,5-trimethyltetrahydro-1,2-oxazin-3-thione and N,N-dimethyl-2-methyl-5-cyano-5-hexanamide, 3-(2-benzylloxycarbonyl-5-propylcarbamoylhexyl)-6,6-dipropyltetrahydro-1,3-oxazin-4-one from 6,6-dipropyltetrahydro-1,3-oxazin-4-one and benzyl 2-methyl-5-propylcarbamoylhexanoate, and 4-(2-cyclohexoxy-carbonyl-5-cyanohexyl)-6-octyltetrahydro-1,3-oxazin-4-one from 6-octyltetrahydro-1,3-oxazin-4-one and cyclohexyl 2-methylene-5-cyanohexanoate.

35

Example 7

Into a reaction vessel there are added 23.4 parts of tetrahydro-1,4-oxazin-3-thione and one part of sodium methoxide. There is then added over a period of 20 minutes 15 parts of acrylonitrile. The exothermic heat of reaction causes the rise in temperature and after this heat subsides there is added 0.5 part of sodium methoxide. After two additional hours the catalyst is neutralized with sulfuric acid. The product is isolated by distillation at reduced pressure. The product corresponds to 4-(2-cyanoethyl)-tetrahydro-1,4-oxazin-3-thione.

45

50

55

60

65

70

75

In like manner employing sodium as a catalyst there are prepared 2-(2-cyanoethyl)-4-octadecyl-3-isooxazolidinethione from 4-octadecyl-3-isooxazolidinethione and acrylonitrile, 2-tetradecyl-3-(2,5-dioctoxycarbonylhexyl)-4-oxazolidinone from 2-tetradecyl-4-oxazolidinone and diethyl α -methylene- α' -methyladipate, and 2-butyl-4-(2-carbamoylpropyl)-5,6-dimethyltetrahydro-1,4-oxazin-3-one from 2-butyl-5,6-dimethyltetrahydro-1,4-oxazin-3-one and methacrylamide.

Example 8

There are mixed in a reaction vessel 20 parts of 2-butyl-5,5-dimethyltetrahydro-1,3-oxazin-4-one and 20 parts of methyl methacrylate. There is added two parts of sodium methoxide in 0.5 part portions at 10-minute intervals. The reaction mixture is then heated to 112° to 118° C. for three hours. Phosphoric acid is added to neutralize the catalyst. The product is isolated by distillation at reduced pressure. The compound corresponds to 2-butyl-3-(2-methoxycarbonylpropyl)-5,5-dimethyltetrahydro-1,3-oxazin-4-one.

Similarly, there are prepared 2-hexyl-4-(2-ethoxycarbonylethyl)-tetrahydro-1,4-oxazin-3-one from 2-hexyltetrahydro-1,4-oxazin-3-one and ethyl acrylate, 3-(2-butoxycarbonylethyl)-5,5-dibutyl-4-oxazolidinethione from 5,5-dibutyl-4-oxazolidinethione and butyl acrylate, and 2-(2-butoxycarbonylpropyl)-5-octyl-3-isooxazolidinethione from 5-octyl-3-isooxazolidinethione and butyl methacrylate.

Example 9

There are added to a reaction flask 20 parts of 6-pentyltetrahydro-1,3-oxazin-2-one and two parts of sodium methoxide. Over a period of 20 minutes there is added a mixture of 20 parts of N-methacrylamide and two parts of sodium methoxide. The reaction mixture is heated at 118° to 125° C. for three hours. The catalyst is then neutralized with sulfuric acid and the product is isolated by distillation at reduced pressure. The product corresponds to 3-(2-methylcarbamoylethyl)-6-pentyltetrahydro-1,3-oxazin-2-one.

There are made in like fashion 3-(2-methoxyoctoxycarbonylethyl)-5-propyl-4-oxazolidinone from 5-propyl-4-oxazolidinone and methoxyoctyl acrylate, 2-(2-methoxycarbonylpropyl)-4-ethyl-5-hexyl-3-isooxazolidinone from 4-ethyl-5-hexyl-3-isooxazolidinone and methyl methacrylate, and 2-(2-methoxycarbonyl-5-benzoxy carbonylhexyl)-3-isooxazolidinone from 3-isooxazolidinone and methyl benzyl α -methylene- α' -methyladipate.

Example 10

There are charged to a reaction vessel 35 parts of 3-(2-methoxycarbonylethyl)-2-oxazolidinone and 52 parts of 2-ethylhexanol. The solution is heated at reflux until water no longer collects in a Dean-Stark separator attached to the vessel. There is added five parts of sulfuric acid and the water separator is replaced by a column and distilling head. The reaction mixture is held at 45° to 150° C. Methanol is removed until the theoretical amount is collected. The reaction mixture is washed with two 50-part portions of aqueous 20% sodium carbonate and 150 parts of water and then dried over anhydrous magnesium sulfate. Two parts of phosphoric acid is added and the mixture is distilled and the product collected at reduced pressure. The product is identified as 3I2-(2-ethylhexoxy)carbonylethyl-2-oxazolidinone.

In a similar way there are prepared 3-(octoxycarbonylethyl)-tetrahydro-1,3-oxazin-2-one, 2-(2-dodecoxycarbonylethyl)-3-isooxazolidinone and 4-(octadecoxycarbonylethyl)-6-butyltetrahydro-1,4-oxazin-3-thione from the corresponding methyl esters.

I claim:

1. As a new composition of matter, an adduct of the compounds

5

10 and

having the formula,

15

- 20 in which L is a three- to four-membered divalent chain containing two to three carbon atoms and one oxygen atom, the available valences of said two to three carbon atoms in said L chain being satisfied by members from the group consisting of a hydrogen atom and alkyl groups whose total carbon content is no greater than eighteen, Y is a chalcogen having an atomic weight of 16 to 32, Q is a member from the group consisting of a hydrogen atom, alkyl groups of one to eight carbon atoms, and the group $-\text{CH}_2\text{CH}_2\text{CH}(\text{CH}_3)\text{T}$, and T is a member from the group consisting of a cyano group, the group $-\text{CONZ}_2$ in which Z is a member from the group consisting of a hydrogen atom and alkyl groups of one to eight carbon atoms, and the group $-\text{COOR}$ in which R is a member from the group consisting of alkyl groups of one to fourteen carbon atoms, alkoxyalkyl groups of two to fourteen carbon atoms, aralkyl and alkaralkyl groups of seven to fourteen carbon atoms, and cycloalkyl and alkylcycloalkyl groups of three to fourteen carbon atoms.
- 25 30 35 40 45 50 55 60 65 70
2. As a new composition of matter, an adduct of 2-oxazolidinone and an alkyl acrylate having the formula,

in which the alkyl portion contains one to fourteen carbon atoms.

3. As a new composition of matter, an adduct of 2-oxazolidinone and an alkyl alkacrylate having the formula,

in which the alkyl portion contains one to fourteen carbon atoms, and the alk portion contains one to eight carbon atoms.

4. As a new composition of matter, an adduct of 2-oxazolidinone and a dialkyl α -methylene- α' -methyladipate having the formula,

65

in which the alkyl portion contains one to fourteen carbon atoms.

5. As a new composition of matter, an adduct of 2-oxazolidinone and

$(\text{C}_{m-1}\text{H}_{2m-1})$

having the formula,

in which m is an integer of one to nine.

6. As a new composition of matter, an adduct of 2-oxazolidinone and

having the formula,

in which m is an integer of one to nine.

7. As a new composition of matter, 3-(2-methoxycarbonylethyl)-2-oxazolidinone.

8. As a new composition of matter, 4-(2-carbamoyl-ethyl)-2,6-diethyltetrahydro-1,4-oxazin-3-one.

9. As a new composition of matter, 3-(2-ethoxycarbonylethyl)-tetrahydro-1,3-oxazin-2-one.

10. As a new composition of matter, 3-(2,5-diethoxy-carbonylhexyl)-tetrahydro-1,3-oxazin-2-one.

11. As a new composition of matter 3-(2-cyanoethyl)-tetrahydro-1,3-oxazin-2-thione.

12. A method for the preparation of an adduct of the compounds

and

having the formula

in which L is a three- to four-membered divalent chain containing two to three carbon atoms and one oxygen atom, the available valences of said two to three carbon atoms in said L chain being satisfied by members from the group consisting of a hydrogen atom and alkyl groups whose total carbon content is no greater than eighteen, Y is a chalcogen having an atomic weight of 16 to 32, Q is a member from the group consisting of a hydrogen atom, alkyl groups of one to eight carbon atoms, and the group $-\text{CH}_2\text{CH}_2\text{CH}(\text{CH}_3)\text{T}$, and T is a member from the group consisting of a cyano group, the group $-\text{CONZ}_2$ in which Z is a member from the group consisting of a hydrogen atom and alkyl groups of one to eight carbon atoms, and the group $-\text{COOR}$ in which R is a member from the group consisting of alkyl groups of one to fourteen carbon atoms, alkoxyalkyl groups of two to fourteen carbon atoms, aralkyl and alkarylalkyl groups of seven to fourteen carbon atoms, and cycloalkyl and alkylcycloalkyl groups of three to fourteen carbon atoms, which comprises bringing together

and

5 at a reacting temperature in the range of about 0° to 200° C. in the presence of a strong alkaline catalyst.

13. A method as in claim 12 in which a temperature range of about 25° to 175° C. is employed.

14. A method as in claim 12 in which the reaction is conducted in the presence of an inert volatile organic solvent.

15. A method for the preparation of an adduct of 2-oxazolidinone and an alkyl acrylate having the formula

20 in which the alkyl portion contains one to fourteen carbon atoms, which comprises bringing together at a reacting temperature in the range of about 0° to 200° C. in the presence of a strong alkaline catalyst 2-oxazolidinone and an alkyl acrylate.

25 16. A method for the preparation of an adduct of 2-oxazolidinone and an alkyl alkacrylate having the formula

30 in which the alkyl portion contains one to fourteen carbon atoms and the alk portion contains one to eight carbon atoms, which comprises bringing together at a reacting temperature in the range of about 0° to 200° C. in the presence of a strong alkaline catalyst 2-oxazolidinone and an alkyl alkacrylate.

35 40 17. A method for the preparation of an adduct of 2-oxazolidinone and a dialkyl α -methylene- α' -methyladipate having the formula

45 in which the alkyl portion contains one to fourteen carbon atoms, which comprises bringing together at a reacting temperature in the range of about 0° to 200° C. in the presence of a strong alkaline catalyst 2-oxazolidinone and a dialkyl α -methylene- α' -methyladipate.

50 55 18. A method for the preparation of an adduct of 2-oxazolidinone and

having the formula

60 65 in which m is an integer of one to nine, which comprises bringing together at a reacting temperature in the range of about 0° to 200° C. in the presence of a strong alkaline catalyst, 2-oxazolidinone and

70 75 19. A method for the preparation of an adduct of 2-oxazolidinone and

having the formula

in which m is an integer of one to nine, which comprises bringing together at a reacting temperature in the range of about 0° to 200° C. in the presence of a strong alkaline catalyst, 2-oxazolidinone and

20. A method for the preparation of 3-(2-methoxy-carbonylethyl)-2-oxazolidinone which comprises bringing together at a reacting temperature in the range of about 0° to 200° C. in the presence of a strong alkaline catalyst, 2-oxazolidinone and methyl acrylate.

21. A method for the preparation of 4-(2-carbamoyl-ethyl)-2,6-diethyltetrahydro-1,4-oxazin-3-one which comprises bringing together at a reacting temperature in the

range of about 0° to 200° C. in the presence of a strong alkaline catalyst, 2,6-diethyltetrahydro-1,4-oxazin-3-one and acrylamide.

22. A method for the preparation of 3-(2-ethoxycarbonylethyl)tetrahydro-1,3-oxazin-2-one which comprises bringing together at a reacting temperature in the range of about 0° to 200° C. in the presence of a strong alkaline catalyst, tetrahydro-1,3-oxazin-2-one and ethyl acrylate.

10 23. A method for the preparation of 3-(2,5-diethoxy-carbonylhexyl)-tetrahydro-1,3-oxazin-2-one which comprises bringing together at a reacting temperature in the range of about 0° to 200° C. in the presence of a strong alkaline catalyst, tetrahydro-1,3-oxazin-2-one and diethyl α -methylene- α' -methyladipate.

24. A method for the preparation of 3-(2-cyanoethyl)-tetrahydro-1,3-oxazin-2-thione which comprises bringing together at a reacting temperature in the range of about 0° to 200° C. in the presence of a strong alkaline catalyst, tetrahydro-1,3-oxazin-2-thione and acrylonitrile.

UNITED STATES PATENT OFFICE

Certificate of Correction

Patent No. 2,852,512

September 16, 1958

Newman M. Bortnick

It is hereby certified that error appears in the printed specification of the above numbered patent requiring correction and that the said Letters Patent should read as corrected below.

Column 10, line 69, claim 4, for "where" read —which—; column 11, lines 45 to 49, claim 12, the formula should appear as shown below instead of as in the patent—

Signed and sealed this 11th day of November 1958.
